BRUSHMAKING MACHINE

John G. Baumgartner, Aurora, Ill.

Application March 24, 1943, Serial No. 480,354

10 Claims. (Cl. 300—3)

1

This invention relates generally to brush making machines and in particular to means for setting the bristles in brush handles.

An object of this invention is to provide an improved mechanism for inserting a tuft and a corresponding staple in a brush handle.

A further object of this invention is to provide an improved staple forming means.

Another object of this invention is to provide a substantially continuous guideway for a staple over its entire path of movement to an inserted position in a brush handle.

A still further object of this invention is to provide a brush making machine which is simple and compact in construction, and capable of quantity production over a long service life with a minimum of adjustments and attention.

A feature of this invention is found in the provision of staple carrying means adapted, during a continuous movement in one direction, to cooperate with a stationary die member to cut a piece of wire to a staple length and with anvil means to form a staple from the cut length of wire.

A further feature of this invention is found in the provision of a brush making machine in which a staple carrying means and nozzle means, for directing a staple and a corresponding tuft to a brush handle, are relatively movable to aligned positions to provide a substantially continuous guideway for the anchor. A bristle tuft is deposited on the nozzle means prior to its movement to such aligned position, so that in the aligned position the tuft is located in the guideway to be engaged by and inserted with the staple in a brush handle.

Further objects, features, and advantages of this invention will appear from the following description when taken in connection with the accompanying drawings in which:

Fig. 1 is a front elevational view of the brush making machine of this invention;

Fig. 2 is a plan view of the machine in Fig. 1 showing the relative arrangement of the operating units and the driving means for the units, with the connecting mechanism between some of the operating units and corresponding driving means being omitted for the purposes of clarity;

Fig. 3 is a view taken approximately along the line 3—3 in Fig. 2 showing the relative arrangement of a pair of rotary handle carrying units forming a part of a means for carrying a formed handle from a handle forming mechanism to related operating units adapted to complete a finished brush;

2

Fig. 4 is a fragmentary sectional view taken along the line 4—4 in Fig. 3 showing the construction of a brush handle holder on one of the rotary handle carrying units;

Fig. 5 is a plan view of the carrying means of Fig. 3 showing additionally the means for transferring a handle from one rotary carrying unit to the second carrying unit and for ejecting a finished brush from the machine;

Fig. 6 is an exploded perspective view showing the relative arrangement of a staple carrying and forming means with nozzle means for guiding a staple and a corresponding bristle tuft to a brush handle;

Fig. 7 is a fragmentary elevational view showing the relative position of the staple carrying means with the nozzle means when a tuft is being deposited on the nozzle means;

Fig. 8 is illustrated similarly to Fig. 7 and shows the relative position of the staple carrying means and nozzle means after a tuft is supported on the nozzle means;

Fig. 9 is also illustrated similarly to Fig. 7 and shows the relative position of the staple carrying means and nozzle means at the time the staple and tuft are to be inserted in a brush handle;

Fig. 10 is an enlarged elevational view of the staple carrying means and nozzle means showing their associated driving mechanism, and their arrangement relative to a picker mechanism and wire feeding means; and

Fig. 11 shows a completed brush made by the machine of this invention.

In the practice of this invention there is provided a machine for making a brush adapted to be used for applying a finger nail liquid. The machine is simple and compact in construction and has all of its operating parts readily accessible for inspection, servicing and repair purposes. Operation of the machine is completely automatic and continuous to produce completed brushes economically and in high volumes. The machine requires only the supplying thereto of wire, bristles, and handle stock and acts otherwise to automatically supply brush handles to

related operating units, drill a tuft-receiving hole in one end of each handle, separate a substantially measured tuft of bristles from a bristle holding magazine, insert a tuft within the drilled hole, secure a tuft within the handle by means of a staple, form the staple from a continuous length of wire, uniformly comb the inserted bristle tuft, trim the bristles in the tuft to the same height, and then eject the completed brush from the machine. It is believed that the invention

will be better understood by first describing the general operation of the machine. The description of the general operation takes in order the series of operations which the machine performs to produce a complete brush.

General operation

As illustrated in the drawings the machine of this invention operates to produce a brush, shown complete in Fig. 11, adapted to be used for applying a liquid polish to finger nails. It is to be understood, of course, that the machine is not limited in its operation to produce only this brush, since by relatively changing the arrangement of parts thereof it may be used to produce any brush of a general construction having a straight handle with a tuft carried at one end. The brush in Fig. 11 is shown as including a wooden handle 15 of straight round form having a shank portion of reduced diameter, and a slotted end portion 16 of larger diameter adapted to be inserted in frictional engagement in a cap or cover 17, of a usual construction, for closing a bottle carrying the liquid to be applied by the brush. The opposite end of the brush has a drilled axially extending hole 18 for receiving a bristle tuft 19 which is secured to the brush handle by a staple 21 anchored in the bottom of the drilled hole.

The stock 22 from which the wooden handles 15 are formed is supplied to the machine in pieces (Fig. 1) which are of a straight round form and supported in a stock holding magazine, indicated generally as 23, in a superposed relation. The magazine 23 (shown also in Fig. 2) includes a horizontal table 24 carrying upright spaced corresponding members 26 and 27, with the members 26 and 27 being arranged in pairs longitudinally of the table 24. Each end 28 of a member 27 is bent outwardly away from a corresponding member 26 to initially support the stock pieces 22 for dropping into a superposed position between the upright members 26 and 27. The end members 27 are constructed of angle iron to support corresponding ends of the stock pieces 22 in substantial vertical alignment.

The lowermost piece of stock 22 has the left end thereof as viewed in Fig. 1, successively fed to the machine in lengths corresponding to a handle length, by feeding means indicated generally as 29, to a position where it is operated on by a rotary combination turning and drilling unit 31 (Figs. 2 and 5). The combination unit in a single operation turns the handle to its two diameters and drills the hole 18. On completion of the drilling and turning operation the machined portion of the stock is releasably gripped, in a holder or clamp 33 (Figs. 3 and 5) substantially concurrently with the cutting of the machined portion to a handle length by a saw 34, so that the formed handle 15 is supported in a holder 33. A plurality of holders 33 are carried in an angularly spaced relation on a rotary table or handle carrying unit 36 supported for rotation in a vertical plane parallel to a second table or handle carrying unit 37. The two tables 36 and 37 are horizontally offset from each other to provide for the alignment axially thereof of a holder 33 with a holder 38, a plurality of which are carried in an angularly spaced relation on the table 37. Each of the tables 36 and 37 is intermittently rotated distances corresponding to the angular spacing of their corresponding holders 33 and 38, respectively, to define the operating stations for the handle 15. Thus at the end of each intermittent rotation of the tables 36 and 37 a holder 33 is in horizontal alignment with a holder 38.

At this operating station of a holder 33 and a holder 38 the handle 15 is moved in a direction axially thereof by a combination transfer and ejector mechanism 39, which operates to transfer the handle from a holder 33 on the table 36 to a holder 38 on the table 37 as will be later fully described.

With the handle 15 in a holder 38 on the table 37 the handle is successively carried to a tuft and staple inserting unit 41, a tuft combing mechanism 42 and a tuft trimmer 43 (Figs. 1 and 2). During the combing of the bristle tuft 19, and as clearly appears in Fig. 1, the slot in the handle end 16 is cut by a saw 44. On the completion of this series of operations a finished brush, while still held in a clamp 38 is rotated by the table 37 to an ejecting station which is just ahead of the transfer station at which a brush handle is transferred to the table 37 from the table 36. At the ejecting station a brush is acted upon by the transfer and ejecting mechanism 39 and ejected or discharged from a holder 38 into a receptacle or the like 46. On reaching the transfer station, therefore, a holder 38 is empty and ready again to receive a handle from a holder 33 on the table 36.

The operating stations for the handle 15 are indicated in Fig. 3 with respect to the rotary table 37, the transfer station being shown at A and the tuft and staple inserting station at B. The combing operation takes place for movement of the handle between the stations indicated at C and D, with the cutting of the slot in the handle end 16 occurring at the station C. The trimming of the bristle tuft takes place at station E, and the finished brush is ejected from the machine at the station F.

Driving means

The general arrangement of the driving means for the machine is best understood from Figs. 1 and 2. The machine includes a horizontal table 47 of a substantially rectangular shape having supporting legs 48. There are four driving motors for operating the machine, a main driving motor 49, a motor 51 for the combination turning and drilling unit 31, a motor 52 for the handle cutting saw 34, and a motor 53 for the slot cutting saw 44. The main motor 49 operates four power shafts, three of which indicated as 54, 56, and 57 are extended in a parallel spaced relation at the left end of the table 47, as viewed in Figs. 1 and 2, the shaft 54 being below the shaft 56 and the shaft 57 above the shaft 56. The motor 49 is belt connected with the shaft 54, which in turn is connected to drive the shaft 56 through gears 58 and 59. The shaft 57 is driven from the shaft 56 through a gear and sprocket means indicated at 61. The fourth power shaft 62 is extended across the rear end of the machine, as viewed in Fig. 2, and is connected in driven engagement with the shaft 56 through a bevel gear connection shown at 63. The shafts 56, 51, and 62 might properly be called cam shafts, since each carries a plurality of cams for operating associated operating units in the machine in a predetermined sequence, as will appear in the following detailed description of the machine.

Handle carrying mechanism

With reference to Figs. 3, 4, and 5 the handle carrying mechanism is seen to include the rotating tables or handle carrying units 36 and 37, previously mentioned in the explanation of the general operation of this invention. The table

36 has a hub portion 106 provided with five angularly spaced spokes 107, with a holding unit 33 being carried at each end of a spoke 107. The rotation of the table 36 is in a plane normal to the longitudinal axis of a stock piece 22, with the stock piece during each feeding operation having the left end portion thereof, as viewed in Fig. 2, projected into the path of movement of the holding units 33. During the operation of the combination unit 31 this left end portion of the stock piece 22 is located between adjacent holding units 33 so that the combination unit 31 moves longitudinally of the stock piece 22 and between adjacent holding units 33 but free of such holding units. Substantially concurrently with the retraction or the movement of the combination unit 31 out of the path of movement of the holding units 33 and the movement of the saw 34 to cut a handle 15 from a stock piece 22, the table 36 moves to a position at which the handle to be cut from the stock piece 22 is between the jaws 115 and 120 of a holding unit 33. The rotation of the table 36 is continuous but intermittent and is accomplished by a suitable pawl and ratchet driving mechanism (not shown) associated with a cam 36a carried on the cam shaft 62 (Fig. 2).

The jaws 115 and 120 (Figs. 3 and 5) are arranged substantially tangentially of the table 36, with the jaw 115 being formed as a part of a corresponding spoke 107 and the jaw 120 being pivoted at the end of a corresponding spoke 107 for movement relative to the jaw 115 in a direction normal to the axis of the table 36. The jaw 120 is normally urged toward a closing position with the jaw 115 by a spring 108. The jaw 120 is in an open position when its corresponding holding unit 33 is at a position to receive the stock piece 22 and is automatically released for closing with the jaw 115 on the piece 22 substantially concurrently with the operation of the saw 34. As a result after a handle is cut from the stock piece 22, the handle is supported in a holder 33 for rotation with the table 36. The jaw 120 is moved relative to the jaw 115 by a vertically extending cam 109, supported on the machine table 47, which has a cam surface 111 of substantially arcuate contour for engaging and opening the jaw 120 against the pressure of the spring 108. The cam 109 holds the jaw 120 in an open position until after the handle 15 is received between the jaws 115 and 120, at which time the jaw 120 is moved out of an engaging position with the cam 109 and is closed on the handle 15 by virtue of the action of the spring 108.

After the handle 15 is thus supported within a holding unit 33 the table 36 is rotated counter-clockwise, as viewed in Fig. 3, to move the supported handle 15 out of the path of movement of the combination unit 31 to permit the machining of a later handle 15. The counter-clockwise rotation of the table 36 moves the holder 33 from the position G at which it received a handle 15 to a next successive position which corresponds to the transfer station A indicated in Fig. 3. As was above explained in the general description of the invention the operating station A designates a position at which a holding unit 33 on the table 36 is in linear alignment with a holder 38 on the second carrying unit or table 37, in a direction axially of the tables 36 and 37. Table 37, like table 36, is intermittently moved to successive positions to carry a handle 15 to related operating units. This intermittent rotation of the table 37 is accomplished by a pawl

and ratchet mechanism (not shown) which is associated with an operating cam 37a on the cam shaft 62 (Fig. 2).

The table 37 is of a substantially disc form and has holders 38, eight of which are indicated in Fig. 3, angularly spaced about its periphery. Although the table 37 is illustrated as having eight like holders 38 and the table 36 as having five like holders 33, the intermittent rotation of the tables 36 and 37 is such that at each position to which a table 36 and 37 is moved, a holder 33 is in alignment with a holder 38 at the operation station A. Each holder 38 (Figs. 3, 4 and 5) includes a stationary jaw 112 and a movable jaw 113 which is normally biased toward a closing position with the jaw 112 by a spring 114. The jaw 113 is of a substantially H-shape in section and is slidably supported on the table 37 in a radially extending recessed portion 116 having a cavity 123 in the bottom thereof. The jaw 113 is retained on the table 37 by the stationary jaw 112 which extends across the recess 116 and is secured to the peripheral portion of the table 37. The spring 114 is positioned in a cavity 117 formed in a slidable jaw 113 and is arranged in compression between the bottom of the recess 117 and a plate-like portion 118 integral with a lever arm 119. The pressure applied by the spring 114 on the jaw 113 is sufficient to support a handle 15 between the jaws 112 and 113 but permits the handle 15 to be moved in a longitudinal direction relative to the jaws. To firmly hold a handle 15 between the jaws 112 and 113 the action of the spring 114 is supplemented by stronger springs 118a arranged in compression between the plate-like portion 118 and the bottom of the cavity 123 and located in the cavity 123 and acting on the movable jaw 113 through the portion 118.

There is an arm 119 and springs 114 and corresponding to each holder 38. Each arm 119 has one end pivoted to the table 37 and an opposite end 130 extended outwardly from the periphery of the table 37 for engaging an arcuate surface 121 on a vertically arranged cam 122 carried on the machine table 47. When an arm end 130 is out of engagement with the cam surface 121 the springs act on the arm portion 118 to press the movable jaw 113 radially outwardly from the table 37. The double action of the springs 114 and 118a on the movable jaw 113 is such as to hold a handle 15 in a substantially firm position between the jaws 112 and 113. When the arm end 130 is in engagement with the cam surface 121 the action of the springs is removed from the movable jaw 113 so that such jaw is moved toward the stationary jaw 112 only by the action of the smaller spring 114. The action alone of the spring 114 on the jaw 113 occurs at the operating stations A and F, for the table 37, for a purpose now to be explained.

With a holder 33 and a holder 38 in relatively aligned positions at the operating station A the handle 15 is transferred from the holder 33 to the holder 38 by means of the transfer and ejector mechanism 39 which includes a pair of plungers or sliding rods 124 and 126 slidably supported in a bearing member 127, carried on the machine table 47, and connected for operation together with a common actuating member 128. The rods 124 and 126 are slidably moved in a plane normal to the tables 36 and 37 and in a direction axially of the handle 15 by means (not shown) operatively connected with the common actuating member 128 and a cam 39a mounted on the cam shaft 56. The plunger 124 is in coaxial align-

ment with a handle 15 at the operating station A and on sliding movement toward the left, as viewed in Fig. 2, or upwardly, as viewed in Fig. 5, engaged and pushes the handle 15 out of a holder 33 and into a corresponding aligned holder 38. The handle 15 is initially retained in a supported position in the holder 38 by the action alone of the spring 114. The operation of the rod 124 is timed relative to the operation of the tables 36 and 37 so that is retracted from a holder 33 prior to any subsequent rotation of the tables 36 and 37. On rotation of the handle 15 by the table 37 to the operating station H (Fig. 3), the lever arm 118 corresponding to the holder 33 previously at the operating station A, moves out of engagement with the cam 122 to permit both the springs 114 and 118a to act on the movable jaw 113 to firmly hold the handle within the jaws 112 and 113. The handle 15 thus transferred to the table 37 is then rotated to the operating station indicated as B in Fig. 3 at which station a tuft 19 and staple 21 are inserted within the drilled hole 18.

Staple forming mechanism

The mechanism for forming a staple 21 includes a pair of elongated horizontal sliding blocks or staple carrying members 129 and 131 arranged in a superposed relation with the block 129 above the block 131 (Figs. 6 and 10). The blocks 129 and 131 are slidably engageable for relative longitudinal movement and slidably supported in corresponding guideways 133 and 134 carried on an upright frame member 132 mounted on the machine table 47. Blocks 129 and 131 have corresponding longitudinally extending mating grooves 136 and 137, respectively, for guidably supporting a staple 21 between the blocks 129 and 131 during a staple inserting operation. The grooves 136 and 137 extend the full length of the blocks 129 and 131 for also guidably supporting a driver 138 for inserting the staple 21 in the brush handle 15.

Ends 139 and 141 of the blocks 129 and 131, respectively, are pivotally connected with driving arms 142 and 143, respectively, which in turn are pivotally connected at spaced points 135 and 140, respectively, to a common arm 144 pivotally supported at one end 146 on the machine table 47. The arm 144 intermediate the connected ends of the driving arms 142 and 143 carries a rotatable portion 147 supported in a following relation with a cam groove 148 formed in one side of a cam 149 carried on the cam shaft 57 (Figs. 2 and 10). Because of the different distances or lengths at which the pivotal connections 135 and 140 of the driving arms 142 and 143, respectively, are spaced from the pivoted end 146 of the arm 144, the blocks 129 and 131 are relatively moved concurrently with their movement together, with the block 129 travelling a greater distance than the block 131 by virtue of the connection 135 of the driving arm 142 being at the free end 145 of the pivoted arm 144. This difference in travel between the blocks 129 and 131 is of a predetermined extent for a purpose which will be later noted.

The free or operating end portions 151 and 152 of the blocks 129 and 131, respectively, (Figs. 6 to 10) are formed along corresponding sides with longitudinally extending cut away portions 150 and 155, respectively, for receiving an anvil 153. The anvil 153 (Fig. 2) is carried at one end 154 of a rocker arm 156 which is pivotally supported at 157 on the side of the frame member 132 oppo-

site from the sliding blocks 129 and 131. The other end 158 of the rocker arm 156 has a lower portion 159 associated with a cam 161 carried on the cam shaft 57. On rotation of the cam 161 the rocker arm 156 is pivoted in a substantially horizontal plane to in turn reciprocate the anvil 153 in a horizontal plane and in a direction transversely of the linear path of movement of the sliding blocks 129 and 131. The cut away portions 150 and 155 in the ends 151 and 152 of the sliding blocks 129 and 131, respectively, are open to each other and together form a pocket or recess which in turn is open to the anchor guiding portions 136 and 137 in the sliding blocks 129 and 131, respectively. It is seen, therefore, that the anvil 153 is reciprocally movable within the pocket, formed by the cut away portions 150 and 155 in the sliding blocks, and across the anchor guideway formed by the grooves 136 and 137. The cut away portions 150 and 155 in the sliding blocks 129 and 131 are of a length to permit a free reciprocal movement of the anvil 153 without interference from the sliding blocks during their movement in a path normal to the path of movement of the anvil.

The lower sliding blocks 131 at its end portion 152 and at the side thereof opposite the cut away portion 155 is formed with a chamfered or bevelled surface 158 (Figs. 6 and 10), of about 45°, which is adapted for sliding and mating engagement with a corresponding bevelled surface 157 formed on a stationary guiding member 158 carried on the frame member 132. The die member 158 is provided with a wire receiving aperture 159 which terminates in the bevelled surface 157, with a wire 161 being fed through the aperture 159 in predetermined lengths by means including feeding rollers 162 and a cam 165 mounted on the cam shaft 57 (Figs. 2 and 10). It is seen, therefore, that the wire 161 fed through the aperture 159 is projected outwardly from the bevelled surface 157 of the die member 158 and into the path of movement of the slidable blocks 129 and 131 to be engaged by their operating ends 151 and 152, respectively. At the zone of engagement of the projected portion of the wire 161 with the block ends 151 and 152 there are provided at such ends grooves 163 and 164, respectively, connected with corresponding grooves 136 and 137, respectively, but normal to the grooves 136 and 137.

The blocks 129 and 131 are shown in Fig. 13 at the beginning of their operating movement, that is in a substantially extreme position to the right, as viewed in Fig. 10 with the end 152 of the lower block 131 being slightly in advance or ahead of the end 151 of the upper block 129. With the blocks in this relative position, the anvil 153 is moved into the path of their movement, while the wire feeding rolls 162 are concurrently operated to project a length of the wire 161 into the path of movement of the blocks and in a position substantially adjacent the operating side 166 of the anvil 153. On movement of the blocks 129 and 131 toward the left, as viewed in Fig. 10, the block ends 151 and 152 move into substantial vertical alignment as they approach the wire projected in their path. Thus as the lower block 131 moves across the aperture 159 the bevelled, slidably engaged surfaces 156 and 157 cooperate to cut the wire 161 at the end of the aperture 159, substantially concurrently with the reception of the cut length of wire within the vertically extending grooves 163 and 164 and against the operating side 166 of the anvil 153. On the con-

tinued movement of the sliding blocks 129 and 131 towards the left, as viewed in Fig. 10, the ends of the cut length of wire are bent over the operating side 166 of the anvil 153 to form the staple 21 concurrently with the location of the staple in the horizontally extending grooves 136 and 137 in the blocks 129 and 131, respectively, as is shown in Fig. 7.

As clearly appears from Fig. 6 the portion 167 of the anvil 153 over which the cut length of wire is staple-formed is of a relatively long length so that during the bending of the cut wire the anvil 153 is capable of being retracted outwardly away from the blocks 129 and 131 without interfering in any way with the forming of the staple 21. Thus when the staple 21 is formed and guidably supported in the grooves 136 and 137 the anvil 153 is removed out of the anchor guideway. From the above description, therefore, it is seen that the lower block 131 coacts with the stationary die member 158 to cut a staple length of wire, with both blocks 129 and 131 cooperating with the anvil 153 to form a staple 21 substantially concurrently with the positioning of the staple within the guiding grooves 136 and 137. On the completion of the staple forming operation, therefore, the staple 21 is slidably supported between the blocks 129 and 131 for insertion in a brush handle 15.

In a timed relation with the forming of the staple 21, and as is illustrated in Fig. 7, a bristle tuft 19 is deposited by a picker member 168, to be later explained, on a horizontal shoulder portion 173 of a nozzle means 171 located intermediate the blocks 129 and 131 and a handle 15 at the operating station B, indicated in Fig. 3, at which operating station a tuft and staple are inserted in the brush handle. The nozzle means 171 is adapted to coact with the grooves 136 and 137 in the blocks 129 and 131, respectively, to provide a substantially continuous guideway for the staple 21 to the handle 15, and the locating of the tuft 19 in such guideway to be engaged and inserted with the staple into the drilled hole 18 of the handle 15.

Nozzle means

The nozzle means 171 (Fig. 6) includes a base member 174 having a top surface which includes the shoulder portion 173, the shoulder being formed by the partial covering of the top surface with an upper nozzle member 176. The base and upper members are of a substantially block form so that the shoulder 173 forms the horizontal portion of a right angle step at the top of the nozzle means 171 and at the end thereof adjacent the sliding blocks 129 and 131. The top surface of the base member 174 and the lower surface of the upper member 176 are provided with horizontal mating anchor guiding grooves 177 and 178, respectively, which extend into mating nozzle or snout portions 179 and 181 on the members 174 and 176, respectively. The nozzle portions 179 and 181 project outwardly from the nozzle means 171 at the end thereof adjacent the rotating table 37 and terminate substantially at the end 16 of the handle 15 carried on the table 37 at the operating station B (Figs. 3 and 5). The anchor guiding grooves 177 and 178 (Fig. 6) in the nozzle means 171, at the ends thereof adjacent the sliding blocks 129 and 131, are flared or bell shaped so that the tuft 19 deposited on the shoulder portion 173 by the picker member 168 is doubled for insertion into the handle 15 as will be later explained. The oppo-

site ends 225 and 226 of the grooves 177 and 178, respectively, are cutaway to form a slot 227 intermediate the nozzle portions 179 and 181 through which the tuft 19 is drawn from the nozzle means 171 after its insertion in the handle 15.

The nozzle means 171 (Figs. 2 and 10) is supported for vertical movement transversely of the path of horizontal movement of the sliding blocks 129 and 131 on one end 182 of a rocker arm 183. The opposite end 184 of the rocker arm 183 is mounted on a shaft 186 rotatably supported in the frame member 132 and extended transversely through the frame member 132. A second arm 185, is carried at one end on a shaft 187 rotatably supported transversely of the frame member 132, with the arms 183 and 185 being on opposite sides of the frame member 132. The opposite end of the arm 185 has a follower portion 188 associated with an operating cam 171a carried on the cam shaft 57. The end of the shaft 187 at the first arm 183 carries an actuating link 189 which acts on the arm 183 to move it downwardly, as viewed in Fig. 10, against the action of springs 189 arranged in compression between the rocker arm 183 and a boss or lug portion 191 on the frame member 132. The movement upwardly of the arm 183, as seen in Fig. 10, is accomplished by the springs 189, which also function to maintain the follower 188 in a following relation with the cam 171a (Fig. 2). On operation of the cam 171a the nozzle means 171 is moved to upper and lower operating position for a purpose which will appear later.

Staple and tuft inserting mechanism

This mechanism includes in combination the vertically movable nozzle means 171 and the horizontally movable relatively slidable blocks 129 and 131. The respective operating means for the blocks 129 and 131 and nozzle means 171 provide for the nozzle means 171 being at its lower operating position at the time the staple 21 is being formed and received within the blocks 129 and 131, this relative position of the nozzle means 171 and the blocks 129 and 131 being shown in Fig. 7. At this position the ends 151 and 152 of the sliding blocks are removed or spaced from the nozzle means 171, and the horizontal shoulder portion 173 is in a position below the anchor guiding groove 137 in the lower block 131. The space between the nozzle means 171 and the blocks 129 and 131 permits a tuft 19 to be carried by the picker member 168 to the shoulder portion 173, the picker 168 being pivotally movable in a vertical plane adjacent the plane of movement of the slidable members 129 and 131.

With a tuft 19 on the shoulder portion 173 and in the slot 211 in the picker member 168, the movement of the blocks 129 and 131 with the staple 21 supported therebetween is continued toward the left as viewed in Figs. 8 and 10. On the continued movement of the blocks 129 and 131 the block 129 is advanced ahead of the block 131 so as to be offset longitudinally relative to the block 131 with the block ends 151 and 152 out of vertical alignment. This continued movement of the blocks takes place while the nozzle means 171 and picker member 168 are retained in their lower operating positions to provide for the block 129 passing over the shoulder portion 173 to a position at which its end 151 is adjacent the upper nozzle member 176 and for the end 152 of the lower block 131 being moved to a position adjacent the

nozzle base member 174. This relative position of the blocks 129 and 131 with the nozzle means 171 and picker member 168 is shown in Fig. 8. As is also shown in Fig. 8 the bristle tuft 19 is within the picker slot 211 but supported on the horizontal surface 173 of the nozzle means 171 and out of an engaging position with the blocks 129 and 131.

In the relative position of the blocks 129 and 131 as shown in Fig. 8, it is seen that there is formed a reversed step portion of right angle shape having a horizontally extending surface formed by a portion of the lower surface of the upper block 129 and a vertically extending surface formed by the end 152 of the lower block 131. With the blocks 129 and 131 retained in this reversed step relation and their ends 151 and 152, respectively, adjacent the nozzle members 176 and 174, respectively, the nozzle means 171 is vertically moved to its upper operating position shown in Fig. 9 concurrently with an upward movement of the picker 168. This upward position of the nozzle means 171 provides for the step portion at the top thereof moving into a complementary relation with the reversed step portion formed by the offset blocks 129 and 131, to linearly align the staple guiding grooves 177 and 178 in the nozzle means with corresponding staple guiding grooves 137 and 136 in the blocks 129 and 131, respectively. By virtue of the positioning of the block ends 129 and 131 adjacent the nozzle means, as was above explained, there is thus provided at the upper position of the nozzle means 171 a substantially continuous guideway for the staple 21 to the handle 15. Because of the longitudinally offset relation of the block ends 151 and 152 it is apparent that the joining portions of the continuous guideway are out of vertical alignment so that at no time is the staple 21 out of engagement with a solid guiding surface.

As was explained above the guiding groove 177 in the top surface of the nozzle base member 174 includes the horizontal step portion 173. Thus the tuft 19, supported on the shoulder 173, is laid across the staple guiding portion 177 and on moving of the nozzle means 171 upwardly to complement the blocks 129 and 131, as shown in Fig. 9, the tuft 19 while still in the slot 211 of the picker 168 is located between the horizontal surface 173 and the lower surface of the upper sliding block 129. Since these two surfaces define in part the staple guideway the tuft 19 is positioned in the staple guideway formed by the staple guide portions 177 and 178 of the nozzle means and the staple guide portion 136 and 137 in the sliding blocks. On driving of the staple 21 by the driver 138, therefore, the bristle 19 is straddled by the staple 21 and removed from the picker 168 for movement through the nozzle means 171 and insertion in the drilled hole 18 in the brush handle 15.

On completion of the inserting operation the blocks 129 and 131 are moved toward the right to their starting position shown in Fig. 10 and the picker 168 is moved to its upper position, as also shown in Fig. 10, while the nozzle means 171 is dropped to its lower operating position to again be ready to receive a bristle tuft 19. On movement of the blocks 129 and 131 toward the left, as viewed in Fig. 10, the cycle of operations providing for the cutting and forming of the staple 21, its reception in a supported position between the blocks 129 and 131 and the movement of the blocks 129 and 131 relative to each other and to the nozzle means 171 prior to a tuft

and staple inserting operation is repeated in the manner above fully explained.

The driver 138 for inserting a staple 21 and tuft 19 into a brush handle 15 is continuously 5 slidably supported in the staple guiding grooves 136 and 137 in the blocks 129 and 131, and during the inserting operation is slidably movable in the continuous anchor guideway formed by the blocks 129 and 131 with the nozzle means 171. The driver 138 is operated through a sliding block 190 slidably supported in way members 192 carried on the frame member 132 (Fig. 10), with the sliding block being pivotally connected to one end 193 of a driving arm 194. The opposite end of the driving arm 194 is eccentrically mounted on the cam 149 to provide for the reciprocation of the driving arm 138 in a timed relation relative to the operation of the sliding blocks 129 and 131 and the nozzle means 171.

As was mentioned above the nozzle portions 177 and 178 of the nozzle means 171 terminate substantially adjacent one end of the handle 15. As is shown in Fig. 5 a slight space is provided 25 between the handle and the nozzle portions to prevent any jamming of the bristle tuft 19 at the end of the nozzle portions during an inserting operation, and also to permit a free passage of the handle 15 into coaxial alignment with the 30 staple guideway provided in the tuft and staple inserting mechanism including the nozzle means 171 and the blocks 129 and 131. This space is additionally increased during the inserting operation by virtue of the movement of the handle 15 by the driving rod 138. Although a spring on a 35 corresponding holding means 38 for a handle 15 retains the handle 15 in a substantially firm position on the rotating table 37, a movement of the handle 15 occurs during an inserting operation due to the impact of the driver 138 in driving the staple 21 to an anchored position in the 40 bottom of the drilled hole 18. This movement of the handle 15 is limited by an adjustable stop means 196 arranged in linear alignment with the handle 15 and to the side of the rotating table 37 45 opposite the nozzle means 171. Since any movement of the handle 15 to a stop position occurs as the result of the moving force being applied thereto through the staple 21, any tendency of a 50 bristle tuft 19 to pass out of a straddled relation with the staple 21 is entirely eliminated, since the staple legs are against the bottom of the drilled hole 18 prior to any movement of the handle 15 to a position against the stop 196.

Picker mechanism

The picker mechanism, shown in Fig. 10, includes the picker member 168 and a vertical bristle magazine 197 for carrying bristle stock 198. The picker member 168 is of a substantially arcuate form and has a radially extending arm 199 mounted on a shaft 201 rotatably supported at the top of the frame member 132 as viewed in Fig. 10. Also carried on the shaft 201 is an arm 202 pivotally connected to one end of a second arm 203 the opposite end 204 of which is in turn pivotally connected to the free end of a driving arm 206, the other end 207 of which is pivotally 60 supported on the machine table 47. Intermediate the ends of the driving arm 206 is a rotary follower portion 208 adapted for following engagement in a cam groove 209 formed in the cam 149. It is seen, therefore, that the cam 149 is 65 constructed to operate the sliding blocks 129 and

131, the driver 138, and the picker member 168 in a predetermined timed relation.

The picker member 168 is pivotally movable across the lower end of the bristle magazine 197 and has a notch 211 therein for cutting and receiving a measured tuft of bristles from the bristle stock 198 to form a bristle tuft 19. The tuft 19 is retained within the notch 211 for carrying to the nozzle means 171 by a buffer member 212 having an arcuate surface in mating slidably engagement with the arcuate picker member 168. The buffer member 212 extends from the bristle magazine 197 to a position above the shoulder portion 173 on the nozzle means 171. On passing of the notch 211 off from the buffer member 212 the bristle tuft 19 is free to fall on the horizontal surface 173 on which it is supported for movement into the path of the staple 21 as was explained above.

Combing mechanism

On completion of the staple and tuft inserting operation, which occurs at the operating station B indicated in Fig. 3, the handle 15 with the tuft 19 inserted within the drilled hole 18 and secured to the bottom thereof by the staple 21 is moved to the operating station C. At this operating station the tuft 19 is acted upon by the combing means 42 (Fig. 1) which includes a series of three combing members 213 pivotally connected at one end 214 to the frame member 132. The members 213 are connected together for concurrent operation by a connecting link 216 and are operated for reciprocal movement across the bristle tufts 19 by means including a driving arm 217 eccentrically mounted on a shaft 218. The shaft 218 carries a pulley 219 which is connected with a driving pulley 221 mounted on the power shaft 54. The combing operation, by virtue of the plurality of combs 213 is continued while the handle is moved from the operating station C to the operating station D as indicated in Fig. 3.

Slot cutting mechanism

The cutting of the slot in the large end 16 of the handle 15, which permits this end portion to be moved into frictional engagement with the cap 17 as is shown in Fig. 11, takes place at the operating station C concurrently with the beginning of the combining operation of the tuft 19. The saw 44 for cutting the slot in the handle 15 is rotatably supported at one end of a rocker arm 222 which is pivotally movable in a direction axially of the handle 15. The opposite end of the rocker arm 222 is pivotally supported on the machine frame 41 with its pivotal support being in substantial coaxial alignment with the motor 53 which operates the saw 44 through a belt connection 223. Pivotal movement of the rocker arm 222 in a timed relation with the rotation of the table 37 is accomplished by operating mechanism including a cam 44a carried on the cam shaft 62 (Fig. 2).

Trimmer mechanism

On movement of the handle 15 to the operating station E indicated in Fig. 3 the combed bristle tuft 19 is trimmed to a uniform height by the trimmer mechanism designated generally as 43 in Fig. 1. This mechanism includes stationary blades associated with a reciprocally movable blade which is continuously operated during the operation of the machine of this invention by means including a cam 43a mounted on the cam shaft 62. The trimming operation completes a finished brush which is ejected from the machine

by the operation of the transfer and ejecting mechanism 39.

Transfer and ejecting mechanism

With reference to Figs. 3 and 5 the ejecting station for the finished brush is indicated at F, at which station it is acted upon by the driver 126 of the transfer and ejecting mechanism 39. As was previously mentioned the drivers 124 and 126 in the mechanism 39 are concurrently operated by virtue of their connection with a common actuating member 128. The drivers 124 and 126 are arranged in a parallel relation but offset from each other a distance corresponding to the distance between adjacent holders 38 on the table 37, and are in alignment axially of the table 37 with adjacent holders 38. Since the driver 124 functions only to transfer a handle 15 from the table 36 to the table 37 it is movable only across the plane of the table 36 in the path of movement of the holders 38. The driver 126, although longer than the driver 124, is located entirely out of the path of movement of the table 36 but is movable across the planes of both the tables 36 and 37 to completely pass through a holder 38 on the table 37.

On operation of the transfer and ejecting mechanism 39, both drivers 124 and 126 are operated together so that a handle 15 is transferred from the table 36 to the table 37 concurrently with the ejection of a finished brush from the table 37. As was previously mentioned an arm 119 associated with a holder 38 (Figs. 3 and 4) is operated on by the cam 122 at the station A to permit the ready insertion of a handle 15 from the table 36 into a holder 38 on the table 37. The operating surface 121 of the cam 122 is of a length to also engage the arm 119 of a holder 38 at the station F so that only the smaller spring 114 acts to retain the jaws 112 and 113 of a holder 38 in a closed position at the operating stations A and F. Thus at the stations A and F, although the handle 15 is releasably supported in a holding means 38, such support is of a nature to permit the ready insertion into and removal of a handle from a holder 38.

The finished brush ejected from a holder 38 at the station F drops into the receptacle or box 46 shown in Fig. 1 which is slidably supported on the machine frame 47 for convenient removal from the machine. The wooden shavings and sawdust resulting from the various operations performed on the wooden handle 15 as well as loose bristles and the like are drawn into suction air ducts 224 having inlet portions prearranged on the table 47. All waste and dirt is thus quickly removed from the machine to prevent any waste accumulations about any of the operating units.

From a consideration of the above description it is seen that the invention provides a brush making machine which is of a compact and rugged construction capable of operating automatically to produce a finished brush on the supply thereto of only handle stock, bristles, and wire. Stock for the brush handles is successively fed to the machine in handle lengths at a predetermined rate corresponding to the time required for machining a length into a handle and the performance of related operations on a machined handle to produce the finished brush. Continuously operated intermittently rotatable handle carrying means are provided with handle holders adapted to automatically engage a handle to carry the handle to various operating units, with

15

further means being adapted to continuously transfer a handle between the holders on separate carrying units of the carrying means to provide for the handle being continuously carried to operating units associated with each carrying unit. The relatively slidable horizontally movable blocks or staple carrying means, during a continuous movement in one direction, cooperate with a stationary wire supporting means to cut a length of wire, and with an anvil means to staple-form a cut length of wire concurrently with receiving the staple being formed for guidable support to a brush handle. The sliding blocks further coact with a vertically movable nozzle means to provide a substantially continuous guideway for the staple to the brush handle and a location of a bristle tuft in the guideway in a position to be straddled by and inserted with the staple into the brush handle. The entire machine is comprised of but a few parts requiring servicing and attention, with the operating portions being movable but relatively small distances so that the machine is capable of high volume production over long continuous operating periods.

Although the invention has been described with respect to a preferred embodiment thereof it is not to be so limited since modifications and changes can be made therein which are within the full intended scope of this invention as defined by the appended claims.

I claim:

1. In a brush making machine, the means providing a substantially continuous guideway for a staple to a brush handle and the positioning of a bristle tuft in said guideway to be engaged and inserted with said staple in said brush handle including in combination horizontal means having a horizontal guide portion for said staple terminating in a reversed step portion at one end of said horizontal means, vertically movable means having a step portion at the top thereof and a horizontal guide portion for said staple terminating at said step portion, with said step portion, when said vertically movable means is in an upper position, being in a complementary relation with said reversed step portion to align said two guide portions to provide said substantially continuous guideway, and means for depositing a bristle tuft on said step portion when said vertically movable means is in a lower position, with movement of said vertically movable means to said upper position locating said bristle tuft in said guideway.

2. In a brush making machine, the means for positioning a bristle tuft in the path of movement of a staple to be engaged and inserted with the staple in a brush handle including in combination a first staple guide portion, a second staple guide portion corresponding to said first guide portion to guidably support an anchor therebetween, with one of said two guide portions being adapted to support a bristle tuft thereon and with the other guide portion including a pair of relatively driven members, and means for relatively moving said guide portions toward each other and in directions substantially at right angles to one another.

3. In a brush making machine, the means providing a substantially continuous guideway for a staple to a brush handle and the positioning of a bristle tuft in said guideway to be engaged and inserted with the staple in a brush handle including in combination horizontally movable means having a horizontal guide portion for said

16

staple terminating in a reversed step portion on said horizontal means, vertically movable means having a step portion at the top thereof and a horizontal guide portion for said staple terminating at said step portion, said two movable means being relatively movable to a position at which said step portion complements said reversed step portion to align said two guide portions to provide said substantially continuous guideway, and means for depositing a bristle tuft on said step portion prior to the relative movement of said two movable means to said complementary position so that at said position said tuft is in said guideway.

4. In a brush making machine, the means for inserting a staple and a bristle tuft therewith into a brush handle including in combination a pair of linearly movable relatively slidable members for guidably supporting a staple therebetween, means for driving said slidable members so that corresponding ends thereof are longitudinally offset from each other during an inserting operation, means having a pair of fixed portions thereon substantially in an L-shape co-acting with said corresponding offset ends of said slidable members to provide a substantially continuous guiding support for said staple to said handle, and means for moving said coacting means to two operating positions, said coacting means in one operating position being adapted to receive and support a bristle tuft thereon between said two offset portions, and in the other of said operating positions compressing the tuft and providing said continuous guiding support for said staple, with said tuft, in said other operating position, being in the path of said staple so as to be inserted therewith during an inserting operation.

5. In a brush making machine, the means for inserting a staple and a bristle tuft therewith into a brush handle including in combination a pair of linearly movable members constructed to slidably support a staple therebetween and means for driving one member beyond the other, means coacting with said linearly movable members to provide a substantially continuous slidable support for said staple to said handle, and means for moving said coacting means to two operating positions, said coacting means in one operating position being adapted to receive a bristle tuft thereon, and in the other operating position compressing the bristle tuft and providing said continuous guidable support for said staple, with said bristle tuft when said coacting means is in said other operating position, being located in the path of movement of said staple.

6. In a machine having mechanism for operating on bristles and staples for manufacturing brushes, the combination including a pair of corresponding adjacent driven members, means for driving one member so that in the extended driven position of the members said one member overlaps the other at corresponding ends, means movable in a direction substantially at right angles to the direction of movement of said members having a stepped portion at the top thereof, with said one member forming with said movable means at said stepped portion a cavity for tuft and staple reception, with said driven members and said movable means having guideway portions therein, and a plunger operating between said members to drive a tuft and staple along said guideway portions to a brush handle position at the outside of said movable means.

7. In a machine having mechanism for operat-

ing on bristles and staples for manufacturing brushes, the combination including a pair of corresponding adjacent driven members, means for driving one member so that in the extended driven position of the members said one member overlaps the other at corresponding ends, means movable in a direction substantially at right angles to the direction of movement of said driven members having a stepped portion at the top thereof, with one part of said stepped portion positioned at the one driven member and another part positioned at the other driven member, and said parts and said members forming a cavity for tuft reception, and means for moving said movable means relative to said members to reduce the size of the cavity for compressing a tuft therein.

8. In a machine having mechanism for operating on bristles and staples for manufacturing brushes, the combination including first movable means having a pair of driven members, means for driving one member so that one extends beyond the other member at corresponding ends to provide a substantially L-shaped configuration at such ends, a second movable means having a pair of fixed portions positioned to provide a substantially L-shaped configuration at one end and inverted relative to the first movable means, and means for synchronizing the movements of said movable means and positioning said means such as to provide a continuous smaller cavity at the end portions to initially receive and then compress and guide a bristle tuft for movement through said second movable means.

9. In a brush making machine, mechanism for directing bristle-tufts and bristle retainers to a brush handle including in combination a first means having a pair of cooperating members driven in one direction, a second means comprising a single unit having a guideway longitudinally thereof and driven in a direction substantially at right angles to the driven direction of the first means, said single unit having one portion offset relative to another portion and extending beyond said another portion in the direction of driven movement of said unit, and means for driving said two members of said first means so that one member extends beyond the other in the direction of driven movement, and said one extended member positioned at said one extended portion, and with said other member engaging said another

5

portion with said members and portions forming a walled cavity therebetween in alignment with said guideway for receiving a bristle tuft and bristle retainer for insertion through the guideway.

10. In a brush making machine having structure with a bristle-tuft received thereon and a staple forming anvil, the means for cutting and carrying a wire to be formed into a staple and thereafter carrying a staple and bristle-tuft therewith, such means including in combination a wire guiding and cutting unit having wire movable therein and having a cutting surface thereon at which the movable wire is positioned, a pair of movable blocks each having a portion at one end thereof for engaging such wire which is outside said unit, with one of said blocks engaging said wire at said cutting surface to coact with said unit to cut a piece of wire from the movable wire, and means for driving said pair of blocks to cause said one block to cut said piece of wire and for driving said pair of blocks to move the cut wire therewith and act with said anvil to form a staple, said driving means thereafter driving said blocks and carrying the staple to a position at the bristle tuft in said machine.

JOHN G. BAUMGARTNER.
